UNITED STATES PATENT OFFICE

154,537

DESIGN FOR A WINDOW VENTILATOR

Alfred F. Fukal, Cambridge, Ohio, assignor to
W. W. Welch Company, Cincinnati, Ohio, a cor-
poration of Ohio

Application September 20, 1947, Serial No. 141,498

Term of patent 14 years

(Cl. D62—4)

To all whom it may concern:

Be it known that I, Alfred F. Fukal, a citizen of the United States, residing at Cambridge, in the county of Guernsey and State of Ohio, have invented a new, original, and ornamental Design for Window Ventilator, of which the following is a specification, reference being had to the accompanying drawing, forming a part thereof.

In the drawing,

Figure 1 is a perspective view of a window ventilator, showing my new design;

Figure 2 is an end view of the fan housing, as viewed from the inside of the room;

Figure 3 is another end view of the fan housing and the panel members, as viewed from the outside with the mounting members shown on top in Figure 1 omitted for convenience of illustration;

Figure 4 is a side elevational view of the panel members without the fan housing;

Figure 5 is a cross sectional view taken sub-

stantially on the line 5—5 of Figure 1, the mounting members shown on top in Figure 1 omitted for convenience of illustration;

Figure 6 is a cross sectional view taken sub-stantially on the line 6—6 of Figure 4;

Figure 7 is a cross sectional view taken sub-stantially on the line 7—7 of Figure 4; and

Figure 8 is a cross sectional view taken sub-stantially on the line 8—8 of Figure 4.

I claim:

The ornamental design for a window ventilator, as shown.

ALFRED F. FUKAL.
